(57) **CLAIM**

The ornamental design for a patient interface frame assembly, as shown and described.

DESCRIPTION

FIG. 1 is a perspective view of a patient interface frame assembly;

FIG. 2 is an alternate perspective view of the patient interface frame assembly of FIG. 1;

FIG. 3 is a right side elevational view of the patient interface frame assembly of FIG. 1;

FIG. 4 is a front elevational view of the patient interface frame assembly of FIG. 1;

FIG. 5 is a top plan view of the patient interface frame assembly of FIG. 1;

FIG. 6 is a rear elevational view of the patient interface frame assembly of FIG. 1; and,

FIG. 7 is a bottom plan view of the patient interface frame assembly of FIG. 1.

The left side elevational view of the frame assembly is the mirror image of the right side elevational view of the frame assembly shown in FIG. 3.
